UNITED STATES PATENT OFFICE.

FRANKLIN DOMINICK, OF NEW YORK, N. Y.

PLUG ATTACHMENT.

Application filed March 23, 1922. Serial No. 546,185.

To all whom it may concern:

Be it known that I, FRANKLIN DOMINICK, a citizen of the United States, and a resident of the city of New York, borough of 5 Manhattan, in the county and State of New York, have invented a new and Improved Plug Attachment, of which the following is a full, clear, and exact description.

This invention relates to electrical fixtures and particularly to an improved connector or plug attachment wherein different forms of plugs or connecting members may be properly accommodated for connecting a source of current to the device using the 15 current.

The object of the invention is to provide an improved connector or plug structure wherein feed wires may be readily connected to either a screw socket or a plug socket.

Another object of the invention is to provide an improved connecting device having a connecting contact formed either as a pair of plugs or as a screw structure and means for receiving distributing wires having 20 25 plugs mounted thereon.

A still further object of the invention is to provide a connecting structure for electric circuits wherein a plurality of independent feed wires may be connected to a single 30 socket.

In the accompanying drawings—

Figure 1 is a side view of a plug attachment or connector embodying the invention, certain parts being broken away for better 35 illustrating the invention.

Figure 2 is an edge view of the attachment or connector shown in Figure 1.

Figure 3 is a sectional view through Figure 1 approximately on line 3—3.

Figure 4 is a sectional view through Figure 2 approximately on line 4—4.

Figure 5 is a view similar to Figure 1 but showing a modified form of the invention, the broken away part being taken on line 45 5—5 of Figure 6.

Figure 6 is an edge view of the structure shown in Figure 5.

Figure 7 is a sectional view through Figure 5 on line 7—7.

Figure 8 is a plan view of the blank used as a contact plate in the structures illustrated in Figures 5 to 7.

Figure 9 is a perspective view of the body or casing shown in Figure 7.

Referring to the accompanying drawings by numeral, 1 indicates the complete attach-

ment or connector designed to receive the contact blades 2 of the respective plugs 3 and at the same time be capable of connection to a pair of sockets designed to receive 60 the knife contacts 4 or to a screw socket designed to receive the screw plug 5. The screw plug 5 is provided with a pair of sockets of a well known construction for receiving the knife contacts 4, said knife contacts being therefore capable of engaging the sockets of plug 5 or engaging permanent sockets in a fixture or wall where knife receiving sockets are provided instead of screw plug receiving sockets. 70

The attachment or connector 1 is provided with a body having a central section 6 and side sections 7 and 8 formed preferably of insulating material and rigidly clamped together by bolts, rivets or other securing 75 means 9. The section 6 is provided with laterally extending lugs 10 and 11 which are adapted to receive the ends of the contact blades 4, said contact blades having suitable apertures. A pair of contact plates 12 and 13 are provided for the section 6 and are formed with apertures so that they may fit over the extensions or lugs 10 and 11. The inner faces of the sections 7 and 8 are provided with contact plates 14 and 15 80 85 which are specially constructed as shown in Figures 3 and 4 so that they will each be provided with a depending member 16 having an aperture for fitting over the respective lugs 10 and 11 and each plate is also provided with sockets 17 as indicated particularly in Figures 2 and 4.

It will be noted that the knife contacts 4 are arranged with one end between the respective plates 12 and 14 and 13 and 15 so 95 that a good contact is always maintained between the knife contacts and the respective contact plates. It will also be noted that in addition to the sockets 17, the contact plates 12 and 14 and 13 and 15 respectively are 100 spaced apart and form a small segmental chamber therebetween whereby the knife contacts 2 of the respective plugs 3 may be positioned at any point around the arc-shaped or curved face 18 of the connector 1. If the knife contacts 2 should be positioned at right angles to the contact plates 12 to 15, they are forced in one of the sockets 17. 105

In the construction shown in Figures 1 to 4, means have been provided for three 110 plugs having transversely arranged knife contacts and ample space is provided for

- three plugs having contacts 2 parallel with the respective contact plates. The respective plates 14 and 15 are provided with raised portions 19 to cause a better contact.
- 5 If desired, the plates 12 and 13 could be convexed to a slight extent and extend into the chamber between the respective contact plates though this is not absolutely necessary. If desired, a space could be provided for 10 more than three plugs 3 or less than three.
- In the construction shown in Figures 4 to 8, means have been presented which are designed to receive two plugs 3. In this 15 form of the invention, there is no segmental chamber between the respective plates as shown in Figure 2 but on the contrary only the T-shaped sockets 20. In this form of the invention instead of the connector or attachment 1' being divided into three sections as shown in Figures 2 and 3, the device is divided into two sections along the 20 line 21 instead of at right angles thereto as shown in Figure 2. By reason of this construction, the bolt or rivet 22 must extend as 25 shown in dotted lines in Figure 5 instead of at right angles thereto as shown in Figure 3. Each of the respective sections 23 and 24 are identical so that the description of one will apply to both.
- 30 Section 24 (Fig. 7) is provided with openings 25 and 26 for accommodating the knife contacts 4, said knife contacts being riveted or otherwise rigidly secured to the respective contact plates 27 and 28. Each of these 35 plates when on a blank is formed as shown in Figure 8. When this blank is bent along the line 29, a substantially U-shaped structure in cross section is provided and inserted into suitable sockets in the section 24. A recess is provided for accommodating the 40 depressed portions 30 which form the sockets for the reception of the contact knives of plugs 3. In this form of the invention, only two plugs may be connected to the attachment or connector 1' while in Figure 1 three 45 may be connected though it is to be understood that any desired number may be provided for according to the requirements of any particular case.
- The arrangement of the attachment 1 with 50 the knife contacts 4 and the screw plug 5, permits the device to be connected to any of the conventional sockets now in common use and at the same time permits the use of a number of plugs 3 from one source of 55 supply.
- What I claim is:—
- In an attachment or connector of the character described, a body formed with a pair of parallel slots, each slot having a plurality of notches extending at right angles to the respective slots, the notches of one slot being opposite the notches in the other slot, a pair of contact plates for each of said slots, one plate on each slot being formed with laterally extending portions fitting into the respective notches of said slots whereby contact prongs set parallel to each other or at right angles to each other may be readily inserted, and a terminal for 70 each pair of plates.

FRANKLIN DOMINICK.
